R. S. KNAGGS

TOY CONSTRUCTION

Filed March 19, 1924

UNITED STATES PATENT OFFICE.

ROY S. KNAGGS, OF NEW YORK, N. Y.

TOY CONSTRUCTION.

Application filed March 19, 1924. Serial No. 700,296.

To all whom it may concern:

Be it known that I, ROY S. KNAGGS, a citizen of the United States, and a resident of the city of New York, borough of 5 Manhattan, county and State of New York, have invented a new and Improved Toy Construction, of which the following is a full, clear, and exact description.

This invention relates to toy construction, 10 and more particularly aims to provide a new and useful constructor unit for a toy of the type including a set of selectively engageable units, whereby said new and useful unit or a plurality thereof may be readily and securely but impermanently connected to other units of the set for the purpose of building up more or less elaborate structural combinations.

A further object is to provide a constructor unit as just characterized, and of the heretofore suggested sheet-like multiple-ply type, but in which the sheet-elements thereof, preferably of cardboard as heretofore also proposed, are permanently connected 20 together at points removed from the bounding edges of the component sheet-members, rather than marginally bent and interfolded so as to produce more than a two-ply thickness at the bounding edges of the 25 finished unit. Constructor units of the kind last described, that is, having the bounding edges of the component sheet-members marginally bent and interfolded, have the disadvantages, among others, that the sheet-members for making up the unit are expensive and troublesome to assemble; that such units are limited to rectangular or at least polygonal outlines; that the units are of at 30 least triple-ply thickness at their marginal portions and of quadruple-ply thickness at 35 their corners, but only of two-ply thickness at points removed from such edges and corners; that the gripping edges intended to be provided by the marginal portions of 40 the two sheet-members for frictionally holding an introduced portion of another unit, are interrupted at each corner; and that the interfolded sheet-members always have 45 a tendency to buckle and separate at their portions intended to lie close to and parallel with each other, thereby to destroy the 50 desired sheet-like character of the unit and the anticipated friction hold of the marginal gripping edges.

55 One of the important objects of the present invention, therefore, is to provide a con-

structor unit which may be made up, and desirably is made up, of a plurality of flat and unfolded sheet-members arranged face to face and permanently secured together to provide sheet-like gripping jaws marginally of the unit, with the sheet members secured together at points removed from the bounding edges thereof and with said jaws uninterrupted all around the 60 unit.

Another object is to provide a new and improved constructor unit in which the securing means is of such character and so applied as to present different portions of the 70 component sheet-members as gripping jaws of different depths, so that a plurality of auxiliary units of dissimilar types may be readily employed in connection therewith, especially for the building up of blocks, 75 columns, gables, and other sub-structures eventually to be joined to produce any desired toy building, bridge, or the like.

Still another object is to provide a two-ply sheet-like constructor unit of the 80 utmost simplicity, and yet one in which all the advantages aforesaid may be obtained; while, also, means may be incorporated to facilitate the rapid inter-engagement therewith of a plurality of other units of the 85 set.

The invention will be more clearly understood from the following description, when taken in connection with the accompanying drawing, showing a preferable embodiment of the new constructor unit, and also showing a part of a constructor set including a plurality of such units and particularly adapted for the making of toy buildings.

95 In this drawing,

Fig. 1 is a perspective view showing a portion of one type of toy building in course of erection;

Fig. 2 is a transverse vertical section, 100 taken on line 2—2 of Fig. 1;

Fig. 3 is a horizontal section, taken on line 3—3 of Fig. 1;

Fig. 4 is a perspective view of the new constructor unit with which the present invention is primarily concerned;

Fig. 5 is an enlarged sectional view, taken on line 5—5 of Fig. 4; and

Fig. 6 is a perspective view of one of the simpler auxiliary units shown in Figs. 1, 110 2 and 3.

The unit T of Fig. 1, it will be noted,

includes merely two flat and unfolded cardboard sheets 7 and 8, arranged face to face and secured together to provide sheet-like gripping jaws marginally of the unit. The 5 sheet 7 is here shown as rectangular, and square, and the sheet 8 is of identical outline except for the cut-away corners 9, the purpose of which corners will be hereinafter explained.

- 10 The securing means for the sheet-members are wire staples 10, which are of well-known type and which provide on opposite sides of the unit, opposed and aligned clinching lengths as marked 10^a in Fig. 5 15 and intervening portions 10^b piercing the unit.

The four staples 10 being arranged as shown, that is, sidewise facing the four corners of the unit, and extended along 20 lines substantially paralleling the diagonal lines of the unit, result in the provision of a unit which has many advantages. In the first place, such staples secure the sheets 7 and 8 together at different distances inwardly of the bounding edges 25 of the unit. This establishes a plurality of dissimilar pairs of gripping jaws along each straight side and at the related corners of the unit. One of these pairs of 30 jaws is what may be termed a pair of strip-type jaws as long as the side of the unit; such, for instance, as shown to the right of the dot-and-dash line 11 of Fig. 4, and which is particularly adapted to receive and 35 securely yet impermanently seize and hold a bent-over marginal strip-like tab such as carried at 12^a by an auxiliary constructor unit 12, as shown in Fig. 6. The stops provided by the converging ends of the pair of staples 40 10 as seen in Fig. 5, and which stops determine the depth of the strip-like pair of jaws just described, are such, it will be seen, as to permit said staples to co-act in providing three other pairs of gripping jaws. One of 45 these latter pairs of jaws is what may be described as a triangular jaw, that is, a jaw located at the corner of the unit, and the inner line or third side of which is at or just outward of and parallel with the staple 50 10 at that corner. Such a pair of triangular gripping jaws is found very useful for constructing buildings of elaborate architecture, and particularly for the making of corner bays, balconies, or the like; in a manner which will be well understood, but which, for purposes of simplicity, is not shown in the drawing. The third and very 55 important type of gripping jaws provided at each side of the unit, as the result of arranging the staples 10 diagonally as described, is what may be termed a central deep-throated pair of gripping jaws located between the dot-and-dash lines 14 of Fig. 4; and which is particularly adapted for receiving and securely yet impermanently 60 65

70 seizing and holding an end portion of a small strip or card member as shown at 15 in Figs. 1 and 3. The purpose of this member, hereinafter called the tying unit, is to attach and lock together each of a pair of contiguous and horizontally matched, partially completed block-compartments including four walls, of which walls, two of the walls, as the walls marked W in Fig. 1, are the floor and ceiling, and of which the other two walls, as the walls marked W¹ in Fig. 1, are a pair of oppositely facing side walls joining floor and ceiling.

75 The staples 10, especially when arranged to provide pairs of dissimilar gripping jaws all around the unit of Fig. 4, as above described, are particularly adapted to bind the jaws of each pair together for normal extension parallel to and in face contact with each other, thus always insuring the 80 secure yet impermanent grip above referred to.

85 In Fig. 1 is illustrated a conventional wing or other subdivision of a house, such subdivision being two stories in height, each story having two "rooms", the "floors" and "ceilings" of which are formed by units of the type shown in Fig. 4. The second-story room to the left of Fig. 1 is shown as 90 topped and finished by a gable or pitched roof 16 formed by a pair of the units of Fig. 6 suitably secured together, as by the application of an adhesive to their bent-over tabs 12^a, at the meeting ends of said units which are to form the ridge of the 95 roof. The similar tabs at the opposite ends of these roof-forming units are inserted and seized between the same marginal strip-like jaws of the unit T of Fig. 1, between which are also inserted and seized similar strip-like tabs of the Fig. 6 units, marked 12^b in Fig. 1, which form the side walls of the "room" the ceiling of which is formed by the unit T of Fig. 1. The tabs at the lower 100 ends of these units 12^b are inserted and seized between the same strip-like marginal jaws of the upper unit W of Fig. 1, between which are inserted and seized the marginal tabs at the upper ends of the two units 105 which form the vertical walls W¹ of Fig. 1. Thus the units T, W, W¹ and 12^b of Fig. 1 110 form a columnar structure, and other similar units may be added as desired to make such column of any desired height; and a plurality of such columns, as clearly shown 115 in Figs. 1, 2 and 3 may be joined and securely locked together by employing the strip-like card members 15.

120 The cut-away corners 9 of the sheet 8 of the unit of Fig. 4 (which corners actually need not be so much cut away as there shown) are present for the purpose of providing protruded flat corner portions of the sheet 7, on which a tab 12^a of a unit 12 of Fig. 6 may be slightly downwardly pressed, 125 130

to force sheet 7 slightly away from sheet 8 at such corner, and thus facilitate insertion of the tab 12^a between the sheets for subsequent speedy adjustment relative 5 to the pair of gripping jaws selected.

With a constructed set of the kind just described, it will be seen that there is practically no limit to the size and particular architectural type of building which may be 10 erected; and this is especially true when it is recalled that the unit of Fig. 4 carries uninterruptedly all around and particularly at the corners thereof, pairs of gripping jaws as above described.

15 The sheets 7 and 8, forming the unit of Fig. 4, and also the sheets forming the units of Fig. 6 and the tying strips 15, are desirably made of a semi-flexible and somewhat resilient material which has a rigidity 20 about that of the ordinary playing card, as light cardboard, celluloid, etc. If desired, the cards or the like constituting the units of Fig. 6 may be suitably colored to represent roof or wall structures having windows 25 or doors, or an uninterrupted wall of clapboards, brick or stone, with special cornice effects; and, also, these cards may be cut out to represent doors, windows, lattice work and the like.

30 I claim:

1. A constructor unit for a toy of the type including a set of selectively engageable units; said unit being constructed of a plurality of sheet members arranged face to face and secured together at points removed 35 from the bounding edges of the sheet members to provide substantially parallel sheet-like gripping jaws marginally of the unit.

2. A constructor unit for a toy of the type 40 including a set of selectively engageable units; said unit being constructed of a plurality of sheet members arranged face to face and secured together at different distances inwardly of the bounding edges of the unit 45 to establish different marginal portions of one sheet member as jaw elements of different sizes for coacting with jaw elements of similar sizes formed marginally of the other sheet member.

50 3. A constructor unit for a toy of the type including a set of selectively engageable units; said unit including a plurality of sheet members of substantially the same outline of elastically flexible material, and wire

staples securing the sheet members together 55 in substantially matching relation to establish resilient gripping jaws between said staples and a boundary of the unit.

4. A constructor unit for a toy of the type 60 including a set of selectively engageable units; said unit including a plurality of sheet members of relatively stiff flexible material and of substantially the same outline, arranged in substantially matching relation, and means securing said sheet members together along lines wholly spaced from any boundary of either member to establish 65 resilient gripping jaws between said means and the perimeter of the unit.

5. A constructor unit for a toy of the type 70 including a set of selectively engageable units; said unit including a plurality of polygonal substantially identical sheet members of elastically flexible material arranged 75 face to face in substantially matching relation, and means securing the sheet members together along lines opposite the corners of the unit to establish resilient gripping jaws between said means and the perimeter of the unit.

80 6. A constructor unit for a toy of the type including a set of selectively engageable units; said unit including a plurality of substantially square, flat and unfolded sheet members arranged face to face in edge 85 matching relation, and spaced wire staples securing the sheet members together near their corners to provide marginal gripping jaws, the lines of such staples substantially paralleling diagonal lines of the square and 90 disposed so as to locate a portion of one staple to act as a throat stop for the jaw at one side of the unit and to locate another portion of said staple to act as a throat stop 95 for the jaw at the side of the unit adjoining the side just mentioned.

7. A constructor unit for a toy of the type 100 including a set of selectively engageable units; said unit including a plurality of polygonal substantially identical sheet members arranged face to face in substantially matching relation, and means securing the sheet members together along lines opposite the corners of the unit, one of the sheet members being cut away at one of its corners to permit the protrusion of the corresponding corner of the other sheet member.

105 ROY S. KNAGGS.
